By His Atty. J. Dennis.

United States Patent Office.

CALEB WHITMORE, OF NORTH VERNON, INDIANA.

Letters Patent No. 81,047, dated August 11, 1868.

IMPROVED ROCK-DRILL.

The Schedule referred to in these Letters Patent and making part of the same.

TO ALL WHOM IT MAY CONCERN:

Be it known that I, CALEB WHITMORE, of North Vernon, Jennings county, State of Indiana, have invented certain new and useful Improvements in Rock-Drilling Machines; and I do hereby declare the following description and accompanying drawings are sufficient to enable any person skilled in the art or science to which it most nearly appertains to make and use my said invention or improvements without further invention or experiment.

The nature of my invention and improvements consists in fastening a cylinder to the drill-stock, with diagonal grooves in its periphery, which grooves traverse on a stationary guide-pin, as the drill and its stock are traversed in the process of drilling; also, in certain automatic devices for holding the drill-stock when it is turned, and traversing the carriage or frame that supports the drill-stock.

In the accompanying drawings—

Figure 1 is a front elevation of a drilling-machine with my improvements.

Figure 2 is a plan of the same.

In these drawings, A A are the side-sills, connected by the cross-sills B B, shown in dotted lines in fig. 1, being covered by the platform B'.

The posts C C are fastened to the sills A A, and connected at the top by the bar D.

The traversing-carriage or frame consists of the sides E E, connected by the bars F F. The tenons of these bars extend through the sides, and project into grooves in the parts C C, which serve as ways for the carriage to traverse in the grooves, being shown by dotted lines in fig. 1.

The bars F F project in front of the sides, as shown in fig. 2, and are perforated for the drill-stock G and guide-bar H.

The drill-stock G is arranged to traverse freely in the bars F F, and is provided with a collar, I, which has a pivot extending through the roller J into a groove in the guide-bar H, to prevent the collar from turning with the drill-stock, which is made to turn freely in the collar, and is prevented from traversing in it by the shoulder under the collar and the ratchet-wheel K, fastened to the drill-stock above the collar.

The shaft L is fitted to turn in boxes N N, fastened to the sides E E, and may be provided with a crank-gear or pulley, to turn it by some moving-power, and carry the tappet or cam P, fastened to the shaft, which cam acts against the roller J, and lifts the drill-stock and drill Q, and allows them to fall by their own weight; and the force of the drill may be increased, when desired, by the spiral spring R, on the stock, above the collar I.

The grooved cylinder S is fastened to the stock G, and traverses with it, when the guide-pin T, acting against the inclined sides of the grooves in the periphery of the cylinder, turns the cylinder and drill-stock a little way every time it is traversed, the guide-pin acting against the inclined sides of the grooves at the lower end of the cylinder when it rises, and the upper end when it falls, alternately.

The spring-pawl U is fastened to the collar I, to catch in the teeth of the ratchet K, and prevent the drill-stock from turning backwards.

To hold the carriage up, and allow it to descend as the hole is deepened, I make the screw V to turn in the nut W, fastened to the bar D, which screw extends down through the bar F of the carriage, and has the bevel-gear X fastened to its lower end, which is turned by the gear Y on the shaft Z, which shaft turns in the sides E E, and extends through a slot in the post C, and may be provided with a crank, to turn it and the screw, to move the carriage up and down, when required.

To turn the screw V and traverse the carriage down automatically, I fasten the ratchet-wheel a to the shaft Z, and the spring-pawl b to the collar I, so that when the stock and collar are traversed, the spring-catch will turn the ratchet one tooth every time the drill-stock advances far enough for the end of the catch to take the tooth, and thus lower the carriage very gradually.

What I claim as my invention and improvement in the above-described rock-drilling, is—

The grooved cylinder S, made substantially as described, with the points of the upper inclined guides between the points of those below, in combination with the stationary guide-pin T, for the purpose of turning the drill automatically as it is traversed.

And in combination with the cylinder and guide-pin thus constructed for turning the drill, the ratchet K and pawl U, for the purpose specified.

And in combination with the devices for turning the drill, the ratchet a and pawl b, and their connections, for traversing the carriage and feeding the drill.
